POLYHYDRIC PHENOL-BISULFITE ADDITION PRODUCT COMPOSITION AND METHOD FOR COLD WAVING

Anacleto Mora, Milan, Italy, assignor, by direct and mesne assignments, of one-half to Nathalie Wollard, New York, N. Y., and one-half to Anacleto Mora, Milan, Italy

No Drawing. Application April 7, 1954,
Serial No. 421,709

11 Claims. (Cl. 132—7)

This invention relates to the permanent waving of hair. It is particularly concerned with the so-called cold wave, and it will be described in its application to that process. In order that the invention may be understood, it is necessary to give a brief review of current theory and practice.

There are known various possibilities of altering in a permanent way the physical appearance of keratinous materials, particularly that of human hair. The methods prevalently used are either of physico-chemical nature (hot treatment with appropriate solutions) or of exclusively chemical nature (treatment at room temperature). Because of their simplicity, the methods of chemical nature have attained the widest popular use and the largest distribution. They are called cold waves and it is with respect to them that we shall be concerned in this disclosure.

Such cold wave methods are based either on the capacity of the chemicals used to cause the swelling of the keratinous materials, or on their ability to break the disulphide bonds of the cystine, which is the main constituent of the keratin and on the successive transformation of the cystine into cysteine, the alteration of the hair during that state of constitution, and the retransformation or regeneration into cystine by the action of oxidizing agents, after the hair has taken the desired form. When the cystine is considered an amino-acid-thiol, it is easy to consider the reactions as based on the part taken by the hydrogen atom of the thiolic group, on account of its lability, in the oxidizing-reducing reactions.

Thus particularly:

The means used for breaking the disulphide bonds by chemical agents are numerous. Mercaptans as thioglycolic acid (patent of Everett G. McDonough No. 2,577,710) have been preferred and largely used. On the other hand, the metallic sulphides (U. S. Patent D. Pye No. 2,183,894) have been used but have now been wholly given up because of the serious inconveniences in their use, the main of which consists of the impossibility of stopping their reducing action at the right time. The sulphites, bisulphites, metabisulphites either with organic or metallic radicals, while largely used for the so-called "hot wave," have been employed in the cold wave method with very inferior results. Hence, at the present

time, no efficient "cold wave" method based on such products may be found in the trade, so far as we know.

The following patents represent the state of the art.

- 5 U. S. A.—No. 2,095,374, patent applic. 1932 (R. Steinbach)
- DR.—No. 635,845, patent applic. 1934 (Coriolan CmbH.)
- B. P.—No 423,845, patent applic. 1933 (Norman)
- U. S. A.—No 2,400,377, patent applic. 1934 (Speckmann)

- 20 B. P.—No. 472,745, patent applic. 1937 (Norman)
- U. S. A.—No. 2,437,965, patent applic. 1944 (Michaels)

We have discovered that, contrary to the affirmations contained in the literature and in some patent specifications, those of such products, that are synergically not in possession of both the property of swelling or hydrolyzing the keratinous materials, and that of breaking the largest possible number of disulphide bonds in the shortest possible time, have little curling power, and are 25 commercially not satisfactory for waving human hair permanently at room temperature. A demonstration of the justness of such an assertion resides in the fact that the curling power of the mercaptans, and in particular of thioglycolic acid, which undoubtedly possesses a high 30 breaking capacity for the bisulphide bonds, is practically null under a pH of 8, whereas it is quite sufficient at a higher pH, viz.: between 9 and 10, because only at such a high pH do the solutions of mercaptan acids present a good hydrolyzing capacity for keratinous materials. It is evident from the above, that only when 35 the optimum properties of breaking the disulphide of the cystine bonds is joined to a good hydrolyzing and swelling capacity of the keratinous material is it possible to obtain an efficient and permanent curling or waving 40 of the hair in the cold.

Technically the thioglycolates give very good results, but their use is not exempted from serious inconvenience. The use of thioglycolates in the so-called cold wave frequently leads to a deep and irreversible morphologic deformation of the hair, which suffers a definitive modification of its physico-chemical structure. Also cases of 50 poisoning, and of alteration of the cutaneous tissues of the persons who handle products containing thioglycolic acid bases are frequently noted; the literature gives many 55 of such cases and there are many publications on the point.

Furthermore, the odor and exhalations of such compositions are not always sufferable and cause many people to suffer from loss of appetite, headache, irritation of the eyes, stomach trouble, and dizziness.

The neutral and acid salts of the anion HSO_3^- , containing a metallic or organic cation combined with the HSO_3^- , have been used for decades in liquid compositions for "hot waves," and their use has been transferred to the "cold wave" technique; they have numerous advantages over mercaptans, viz.: they have a very low level of toxicity, which may be considered zero under normal conditions; they have no disagreeable odor and they have very good solubility and stability in solution at the various pH's used for waving. However, they have a negative property of great practical importance, the low ability of sulphites, bisulphites, metabisulphites, thiosulphites

to break a sufficient quantity of bisulphide bonds of the cystine contained in the keratinous material at room temperature, in a short time. Clarke (J. Bil. Che. 1932: 97-235) has indeed demonstrated that bisulphites will reduce into cysteine only one half of the cystine submitted to the treatment, whereas the other half is transformed to sulphonic S-cysteine acid:

which is not reversible into cystine. It follows as a consequence that in the processes based on the use of sulphites, bisulphites, etc. only one half of the bisulphide bonds

of the cystine may be regenerated by the oxidizing treatment to which the keratinous material is submitted, the other half being practically lost, because the sulphonic S-cysteine acid is not reversible into cystine.

For the foregoing reasons, the methods till now applied for curling or waving keratinous materials at room temperature with derivatives of the HSO_3^- anion have been imperfect. Furthermore, those methods require too long a period of contact with the hair to be interesting to the trade; they exert a modifying action on the structure of the keratinous material by virtue of their hydrolyzing power rather than by breaking the bisulphide bonds, and the hydrolyzed material may not be reconverted by the successive oxidizing operation.

On account of bad effects resulting from long contact of the hair with the waving liquids, as specified in the various prior art patent specifications dealing with the subject, the liquids must be either acid or alkaline to reduce the time of contact and they are accordingly possessed of a marked hydrolyzing power, they swell the hair and the swelling is hard to remove, and the wave that results does not possess sufficient properties of elasticity, and is weak and without vitality. Furthermore, the long contact of the bisulphites, especially of those with metallic cations of acid or alkaline pH, causes hair decoloration. These deficiencies are the more apparent as the treatments are made on hair that had previously been oxygenated or dyed. A particular hydrolyzing and hair swelling has also been discovered to result from the use of the bisulphites derived from organic bases.

It is an object of this invention to produce a non-poisonous waving solution which combines the optimum properties of breaking the disulphide bonds of the cystine with good hydrolyzing and swelling capacity for the keratinous material, and thus to obtain an efficient and permanent curling and waving of the hair in the cold.

It is another object of the invention to wave hair at room temperature adequately, quickly, with a contact with the waving liquid on the order of 10-30 minutes, without appreciably swelling or permanently modifying the chemical structure, color, state, or nature of the hair, with a solution of pH in the neutral range, without irritation to the skin, without harmful effect on the operator or the subject, and without disagreeable odors.

The objects of the invention are accomplished, generally speaking, by the use, in the waving of hair, and particularly in the cold waving of hair, of compounds resulting from the reaction of metal, and of amine, bisulphites on polyphenols. The class of polyphenols is preferred which will react in its tautomeric (ketonic) form. The compounds are prepared from the polyphenols and the amine or metal bisulphites with a pH in the neutral or alkaline range, from pH 6 to pH 9, and are used in aqueous medium as lotions which require only a reasonable time to produce the necessary change in the keratin and may thereafter be washed out with oxidizing solutions which regenerate the constituents of the waved hair. The invention includes many advantageous modifications

which will be discussed hereinafter in connection with the specific description of the invention. The preferred polyphenol is hydroquinone, but resorcinol, and phloroglucinol and catechol are useful. These preferred members do not exclude the use of the other members of the class of polyphenols.

The bisulphites that may be reacted with polyphenols to produce the new compounds may have a metallic cation, and among such the alkali metal bisulphites are preferred, or the cation may be an organic radical constituted by an amine-aliphatic base having one nitrogen atom. Thus, bisulphites of methylamine, ethylamine, butylamine, propylamine, of alkanol amines such as ethanolamine, of secondary bases such as dimethylamine and diethanolamine and of tertiary amines such as trimethylamine and triethanolamine have been used and illustrate the class of reagents. In practical use, however, only the primary amines are employed as their resulting products are quite superior to the more complex members of the class. Thus, monoethylamine, monomethylamine, and monobutylamine are preferred. Monoethanolamine gives acceptable results, but less desirable than those obtained from the preferred compounds.

It has been established that the lotions of the preferred substances possess at room temperature a curling or waving power which is very much superior to that of the prior art bisulphitic solutions. Further, it has been discovered that said derivatives have maximum waving power at a pH about 6.4 to 6.8. Thus, it is possible to produce neutral solutions that are practically odorless, harmless, and efficient.

After having experimented with numerous methods and products, we have discovered that this series of compounds presents the following advantages:

(a) At room temperature to produce durable and technically unobjectionable waving or curling with a contact of the liquids between 10 and 30 minutes;

(b) Absence of appreciable swelling or permanent modification of the chemical structure, and of the state or nature, of the treated materials;

(c) Maximum curling or waving capacity with a pH the value of which is about 7;

(d) No phenomenon of irritation in the cutaneous tissues;

(e) No disturbing or disagreeable odors.

The derivatives forming the object of this invention, and which have proved in practice to be in possession of a curling or waving capacity superior to that of the derivatives till now used of the bisulphitic anion, are the products of the reaction of polyphenols with the bisulphites of metallic or organic cation. Evidently, the addition of the polyphenolic group, which fulfills in accordance with the cases a more or less marked reducing action, contributes to increase the percentage of cystine reduced to reversible cysteine, and to stop the formation of sulphonic S-cysteine acid which results from the use of simple bisulphites: for this reason the quantity of cystine which can be disposed of is greater, when the definitive reconstruction of the keratinous material is made, and a consequent more integral reconstruction of the primitive state of the same is obtained, when it is submitted to the final oxidizing treatment.

As it is known, some polyphenols, and particularly the dihydroxy and trihydroxy-benzenes have the property besides to react normally to also react in their ketonic form; for instance, resorcin may react in its normal structural form (1) or in the ketonic form (2).

These ketonic forms of the preferred polyphenols have the property to react with the bisulphites.

So for instance:

The ketonic form of the resorcin combined with a bisulphite gives a product that corresponds with the following formula:

Paradioxybenzene (hydroquinone) in its ketonic form combined with a bisulphite produces a salt of the dihydroxy-1-4-hexamethyltrisulphonic acid:

Pyrogallol (pyrogallic acid) in the ketonic form combined with a bisulphite produces a bisulphitic derivate of the oxo-3-dihydroxy-5-6-tetrahydroxy-1-2-3-4-benzensulphonic acid.

Phloroglucinol in its ketonic form produces derivates that are different depending upon whether 1, 2 or 3 of the ketonic groups of its tautomeric form fix the acid salt.

Further, it has been discovered that said derivates give the maximum result at a pH between 6 and 9 with an optimum around 7. Thus, it is possible to produce neutral solutions that are practically odorless.

Also the nature of the bisulphitic molecule brought to react with the polyphenols has a certain importance, and, by varying it, it is possible to get a differentiation of the practical results.

The following examples illustrate, but do not limit the invention to the particular reactants and conditions in them stated.

Example 1

100 parts by weight of monoethylamine were dissolved in 100 parts by weight of water and SO_2 gas was bubbled through the solution until the pH was in the range 6.4 to 6.8 while maintaining the temperature below about 40° C. In carrying out this portion of the process, the pH may sometimes drop below 6.4, in which case the addition of SO_2 should be stopped and enough monoethylamine be added to bring the pH within the stated range.

350 parts by weight of the product from the foregoing reaction were mixed with 10 parts by weight of hydroquinone in 700 parts by weight of water. 3 parts by weight of stannous chloride ($SnCl_2 \cdot 2H_2O$) were added as a catalyst. The stannous chloride is not essential, as the reaction proceeds without it, but it is beneficial and an additional and valuable part of the invention. The solution was allowed to stand for about two days at room temperature and at that time it had become golden in color and was ready for use. It was stable, and could be stored for extensive periods of time without loss of efficiency.

In producing the lotion that is used on the hair, this product was dissolved in an aqueous medium such as pure water. Up to 70% of alcohol can be used if desired in the solution, but in general the lotion is a simple water solution of the product.

The tin chloride can be replaced by other bivalent salts, for instance, by the halides, particularly the chlorides, of palladium, platinum, rhodium, bismuth, iron, cobalt and copper, but tin chloride is preferred.

Instead of using SO_2 gas for the reaction with monoalkylamine, sodium bisulfite or sodium hydrosulfite and their equivalents may be used.

The product of the reaction between monoethylamine and SO_2 is monoethylaminebisulfite which reacts to form a product having the desired property.

The oxidizers are oxidizing agents soluble in water, such as perborates, persulfates, hydrogen peroxide, perchlorates, chlorates, bromates, and such things as urea derivatives of hydrogen peroxide. The oxidizing agents can be used directly after solution in water, or in the presence of acid, of which tartaric, citric, lactic, phosphoric, hydrochloric and sulfuric may be used.

Example 2

Monoethylamine was reacted with sulphur dioxide as in Example 1 after which 450 parts by weight thereof were taken and mixed with 30 grams of hydroquinone and 3 grams of tin chloride in 820 parts of water. This produced a solution useful for a different type of hair than that of Example 1. The water content in the final product of Example 2 can be varied between 700 and 900 parts and still retain the full utility of the solution, while adapting it to different types of hair and to different rates of treatment. It is used in the more concentrated range when fast action is desired. Outside the stated range of concentration, the efficiency of the solution decreases, although its utility persists.

Example 3

Resorcin was reacted with sodium bisulfite producing a compound having the formula $Na_3C_6H_9S_3O_11$. The technique of Example 1 was employed using sodium bisulfite in place of monoethylamine bisulfite. The resorcin and sodium bisulfite were present in approximately equimolecular parts. The reactants were boiled 8 hrs. under reflux with the admission of a light current of SO_2 to the reaction mass. Tin chloride catalyst was used.

150 cc. of 99% (glacial) acetic acid was dissolved in 350 cc. of water containing H_2O_2 and was employed in oxidizing hair which had been treated with the product of Example 3. After the oxidation, the hair was rinsed in lukewarm, pure water. In both this example, and in Example 6, where this oxidizer was also used, the hair was soft, lustrous, well curled and possessed of a very natural appearance. In using phosphoric acid, amounts equivalent to acetic acid in the present example were successfully employed on hair treated by the product of Example 1.

Example 4

Monomethylamine bisulfite was prepared as in the first part of Example 1 and the product was reacted with hydroquinone utilizing a similar technique.

Example 5

Sodium bisulfite was reacted with phloroglucinol and similarly employed.

In making up the working solutions for application to the hair, it is advisable to compute the weight percentage of the actual product of the polyphenol and bisulfite in the lotion. This may vary widely, but concentrations for useful solutions lie generally between 3 and 60% by weight.

In applying the solution to the hair, the ends of the hair are to be trimmed, if they are split or contain the remains of an old permanent, the hair should be shampooed and thoroughly rinsed and dried. Then a wave lotion is applied to a strand of hair, the wet strand is wound on a bigoudi, and all the hair is similarly done, strand by strand, being wetted with the solution and wound on curlers. When all the curls are wound, the hair is again thoroughly wet with the solution and then enclosed within a scarf or a turban for about 20 minutes. The average processing time for easy-to-wave hair, or for hair with some natural curl, is about 20 minutes; for normal hair 30 minutes; and for children and difficult hair 40 minutes. When the time is up, with the hair still wound on curlers, it is rinsed thoroughly in lukewarm water to remove the lotion, and blotted with a towel. The regenerator or oxidizer is now applied and is allowed to remain on the hair for about five minutes, and the oxidizer is washed out in lukewarm water.

Example 6

An oxidizer was made by dissolving 26% of H_2O_2 in water, and hair which had been impregnated with the product of Example 1 was treated thereby.

7
Example 7

With a water solution containing 20% circa of the product obtained from the reaction of 5 g. of resorcinol with 15 g. of sodium bisulphite brought to a pH of 7-7½ by means of ammonia, the hair is made wet and wound onto bigoudis, the head being then covered with a towel and a cap, preferably of plastic material. The solution is left to act for about 15-20 minutes; then the hair is rinsed with abundance of water (lukewarm), and afterwards the bigoudis are wet for five minutes with an acid solution in the quantity of 500 cc. and containing about 10% by volume of hydrogen peroxide. Successively, the bigoudis are opened and the hair thoroughly washed with water. Finally, the usual waving operation may be made.

Example 8

With a water solution containing 22% of the product obtained from the reaction of 6.3 g. of phloroglucinol with 15.6 g. of bisulphite of sodium brought to a pH of 7-7½ by means of ammonia, the same operations of Example 7 are made.

Example 9

With a water solution containing 22% of the product obtained from the reaction of 17 g. of bisulphite of mono-methylamine with 5 g. of paradioxybenzene brought to a pH of 7-7½, the same operations as per Example 7 are made.

The solutions are used at room temperature, and it is of importance that the process of transformation of the cysteine into cystine by means of oxidizing agents be made accurately. It has been observed that the prolonged washing with water only, as specified in several patent specifications, is not sufficient to retransform the cysteine into the cystine contained in keratinous materials, and therefore the curlings or wavings deriving from them are of short duration; for this reason, it is necessary to make use of an oxidizing agent, the efficiency of which will be particularly good if made lightly acid.

The principles of the invention may be employed for straightening curly hair as well as for curling straight hair. Various methods of applying the process to the hair or other keratinous material can be adopted without departing from the scope of the invention.

As many apparently widely different embodiments of the present invention may be made without departing from the spirit and scope thereof, it is to be understood that the invention is not limited to the specific embodiments.

What is claimed is:

1. A method for cold waving of hair, which comprises wetting the hair at room temperature with an aqueous lotion containing essentially 0.5 to 60% of an addition product of one mol of a polyhydric phenol and at least three mols of a bisulfite, at a pH of 6 to 9, and thereafter wetting the hair with an oxidizing agent in aqueous medium.

2. A method for cold waving of hair, which comprises wetting the hair at room temperature with an aqueous lotion containing essentially 0.5 to 60% an addition product of one mol of hydroquinone and at least 3 mols of monoethanolamine bisulfite, at a pH of 6 to 9, and thereafter wetting the hair with an oxidizing agent in aqueous medium.

3. A method for cold waving of hair, which comprises wetting the hair at room temperature with an aqueous lotion containing essentially 0.5 to 60% an addition prod-

uct of one mol of a polyhydric phenol and at least 3 mols of a bisulfite plus a small amount of a bivalent metal halide sufficient to catalyze the formation of said addition product.

5 4. A method for cold waving of hair, which comprises admixing in aqueous solution one mol of a polyhydric phenol and at least 3 mols of a bisulfite with a catalytic amount of a bivalent metal halide to effect formation of a polyhydric phenol-bisulfite addition product, wetting the hair at room temperature with an aqueous lotion containing essentially 0.5 to 60% of said product, at a pH of 6 to 9, and thereafter wetting the hair with an oxidizing agent in aqueous medium.

15 5. A method of forming a cold wave lotion, that comprises admixing in aqueous solution one mol of a polyhydric phenol and at least 3 mols of a bisulfite, in the presence of a catalytic amount of a bivalent metal halide, and maintaining such solution at room temperature to form a polyhydric phenol-bisulfite addition product.

20 6. A method of forming a cold wave lotion, that comprises admixing in aqueous solution 1 mol of hydroquinone and at least 3 mols of monoethylamine bisulfite, in the presence of a catalytic amount of a bivalent metal halide, and maintaining such solution at room temperature for at least two days.

25 7. A hair waving lotion consisting essentially of an aqueous solution of 0.5 to 60% of an addition product one mol of a polyhydric phenol and at least 3 mols of a bisulfite, at a pH of 6 to 9 plus a small amount of a bivalent metal halide sufficient to catalyze the formation of said addition product.

30 8. A hair waving lotion consisting essentially of an aqueous solution of 0.5 to 60% of an addition product of 1 mol of hydroquinone and at least 3 mols of monoethylamine bisulfite reacted at room temperature in the presence of a stannous chloride catalyst for at least two days.

35 9. A hair waving lotion consisting essentially of an addition product one mol of a polyhydric phenol and at least 3 mols of a bisulfite, in a concentration of 0.5 to 60% in a solvent of the class consisting of alcohol and water, at a pH of 6 to 9, also containing a catalytic amount of a metal halide.

40 10. A composition consisting essentially of 1 mol of a polyhydric phenol and at least 3 mols of a bisulfite, in the presence of a catalytic amount of a metal halide, at a pH of 6-9 in aqueous solution.

45 11. A composition consisting essentially of 1 mol of hydroquinone and at least 3 mols of monoethylamine bisulfite, in the presence of a catalytic amount of stannous chloride, at a pH of 6-9 in aqueous solution.
